UNITED STATES PATENT OFFICE.

ALVA K. HINCHMAN, OF PHILADELPHIA, PENNSYLVANIA, ASSIGNOR OF ONE-FOURTH TO CHARLES H. MORTON AND ONE-FOURTH TO CHARLES H. QUIMBY, BOTH OF PHILADELPHIA, PENNSYLVANIA.

GOVERNOR VALVE

1,406,011.

Specification of Letters Patent.

Patented Feb. 7, 1922.

Application filed September 18, 1920. Serial No. 411,126.

To all whom it may concern:

Be it known that I, ALVA K. HINCHMAN, a citizen of the United States, residing at Philadelphia, in the county of Philadelphia and State of Pennsylvania, have invented new and useful Improvements in Governor Valves, of which the following is a specification.

This invention relates to new and useful 10 improvements in governor valves, particularly adapted for fluid pressure engines of the character having high and low pressure chambers with a balance piston for regulating the flow of fluid pressure from the high 15 pressure chamber to the lower pressure chamber and has for its primary object the provision of a piston so constructed that its stem will form a passage between the chambers when the high pressure chamber is open 20 to receive fluid pressure from a source.

Another object of this invention is the provision of the piston with one of its heads so constructed that it will act as a combined 25 valve and passageway.

A further object of this invention is the provision of an adjusting means adapted to vary the stroke of the piston to permit the device to be used in conjunction with fluid 30 sources varying in pressures, but still permit a pre-determined amount of pressure to be delivered by the governor to a device.

With these and other objects in view, as will become more apparent as the description proceeds, the invention consists in certain 35 novel features of construction, combination and arrangement of parts as will be hereinafter more fully described and claimed.

For a complete understanding of my invention, reference is to be had to the following 40 description and accompanying drawing in which:

Figure 1 is a vertical sectional view of a governor valve for engines constructed in accordance with my invention.

Figure 2 is a horizontal sectional view taken substantially on the line 2—2 in Figure 1, and

Figure 3 is a vertical sectional view illustrating a modified form of my invention.

Referring to the drawings in detail, the numeral 1 indicates a body or casing that has formed in one end a high pressure chamber 2 of considerable length and of a comparatively small diameter and which cham-

ber opens outwardly through one end of the 55 body or casing 1, to have connection with a power source (not shown) or in other words to form an inlet port 3 to the high pressure chamber. A comparatively long piston 4 is 60 slidably mounted in the high pressure chamber 2 and is provided with a transverse passage 5 communicating with a passage 6 that opens outwardly through one end of said piston to permit the fluid pressure to enter the passage 5 from the inlet port 3. By-passes 7 are formed in the body or casing 1, and have communication with the high pressure chamber adjacent each end thereof so that when the passage 5 of the piston 4 is in alignment with the by-passes 7, the fluid 65 pressure can pass into the high pressure chamber 2 from the intake port 3, the piston 4 acting as a valve for controlling the fluid 70 pressure into the high pressure chamber 2.

A low pressure chamber 8 is formed in the 75 body or casing 1, and is of a considerably larger diameter than the high pressure chamber 2 and is closed by a removable cover 9 having an outlet port 10, adapted to be connected with a fluid engine in any well 80 known manner. An opening 11 is formed within the body or casing 1, between the high and low pressure chambers and defines walls 12 provided with openings to slidably receive a piston stem 13, one end of which 85 is secured to the piston 4 while its other end is detachably secured to a piston 14 located in the low pressure chamber 8 and of an area greater than that of the piston 4.

Stuffing boxes 15 are secured in the walls 90 12 to establish a leak-proof connection between the piston stem 13 and said walls and the piston stem 13 is provided with a passage 16 that opens outwardly through one end thereof and communicates with 95 openings 17 formed in the stem adjacent the piston 4. Thus it will be seen that the fluid pressure within the high pressure chamber 2 can pass into the low pressure chamber 8 and when the pressure reaches a predetermined degree in the low pressure chamber 8, the piston 14 is forced downwardly, causing the piston 4 to move downwardly bringing the passage 5 out of registration with the by-passes 7 thus preventing fluid 100 pressure from the source or intake ports 3 from entering the high pressure chamber 2. As the degree of pressure diminishes in the 105

low pressure chamber 8, the high pressure from the intake port forces the piston 4 upwardly bringing the passage 5 into registration with the by-passes 7 permitting the fluid pressure to enter the high pressure chamber and pass into the low pressure chamber 8 by way of the passage 16 through the piston stem 13.

A passage 18 is formed in the body or casing 1, and communicates with the intake port 3 and receives an extension 19^a of a by-pass pipe 19, the upper end of which is connected with a port 20 communicating with the low pressure chamber 8. A valve 21 is located in the by-pass pipe 19 which provides for directly conveying fluid pressure to the low pressure chamber 8 from the intake port 3, the amount admitted being controlled by the valve 21. By this arrangement the low pressure chamber 8 can receive a higher pressure of fluid than would be obtainable through the passage 16 of the piston stem 13, or in other words, fluid pressure from the intake port 3 can be introduced directly into the low pressure chamber 8 and thence to the engine connected to the low pressure chamber permitting the engine to run on a high pressure obtainable directly from the source.

A port 22 communicates with an equalizing chamber 23 formed by the lower face of the piston 14 and one of the walls 12, and said port 22 has connected thereto a pipe 24 which is in turn connected to the by-pass pipe 19 and is provided with a valve 25. The by-pass pipe 19 is provided with valves 26 and 27 arranged above and below the pipe 24. When it is desired to increase the amount of pressure in the low pressure chamber 8, the valve 26 is closed and the valves 21, 25 and 27 are opened permitting fluid pressure to pass directly into the equalizing chamber 23 from the intake port 3, thus requiring a large amount of pressure to be had in the low pressure chamber 8 before the pistons 14 and 4 will be forced downwardly to stop the supply of pressure to the low pressure chamber 8 from the high pressure chamber 2. A port 28 is formed in the body or casing 1 and communicates with the high pressure chamber 2 and has connected thereto a pipe 29 which is in turn connected to the by-pass 19 between the valves 27 and 21 and said pipe 29 is provided with a valve 30. With the valve 27 closed and with the valves 21 and 30 open, fluid pressure directly from the intake port 3 can be introduced into the high pressure chamber 2 in the desired amount by regulating either the valves 21, or 30. When the fluid pressure is admitted to the high pressure chamber 2, by way of the by-pass pipe 19, it produces means whereby the device can be regulated

to decrease the amount of fluid pressure in the low pressure chamber 8.

The closure plate or cap 9 is provided with adjusting screws 31 which provides means whereby the stroke of the pistons and their stems can be varied for the purpose of regulating the amount of fluid pressure to the low pressure chamber 8. By adjusting the screws 31 in the direction of the piston 14 will shorten the stroke of said piston and will not permit the passage 5 to fully register with the by-pass 7 thus reducing or retarding the flow of fluid pressure to the low pressure chamber from the high pressure chamber and from the intake port to the high pressure chamber.

The by-pass pipe 19 is provided with a draining valve 32 which will permit said pipe to be drained whenever desired.

Referring to Figure 3 which illustrates a modified form of my invention, the only difference residing in this form of my invention over what has been heretofore described and illustrated in Figure 1, is that the high pressure chamber 2 is of a greater size than the high pressure chamber 2 shown in Figure 1. By having the high pressure chamber 2 larger permits a greater pressure in the low pressure chamber, as it requires a greater pressure in said low pressure chamber to force the piston downwardly for bringing the passage 5 out of registration with the by-pass 7.

While I have shown and described the preferred embodiment of my invention, it will be understood that minor changes in construction, combination and arrangement of parts may be made without departing from the spirit and scope of the invention as claimed.

Having thus described my invention, I claim:

1. A governor valve comprising high and low pressure chambers having inlet and outlet ports respectively, a piston stem extending into each chamber and having a passageway therethrough communicating with said chambers, pistons secured to said stem and located in said chambers and one of said pistons having a passage and a port communicating with the passage and with the intake port, and said high pressure chamber having by-passes communicating therewith and the passage of said pistons adapted to align with said by-passes when the piston is in one position and moved in said position by forces acting against the other piston.

2. A governor valve comprising high and low pressure chambers having inlet and outlet ports respectively, and said low pressure chamber being of a diameter greater than the diameter of the high pressure chamber, a hollow piston stem in said chambers and

- capable of reciprocatory motion, a comparatively large piston secured to the stem and located in the low pressure chamber, a comparatively long and small piston secured 5 to said stem and located in the high pressure chamber, and having a passage and a port communicating with said passage and intake port, said high pressure chamber having by-passes communicating therewith adjacent each end thereof, said passage of the piston adapted to align with the by-passes when said piston is in one position and moved in said piston by the forces, acting 10 against the last named piston.
- 15 3. A governor valve comprising a casing having high and low pressure chambers provided with inlet and outlet ports respectively, said casing having by-passes communicating with the high pressure chamber 20 adjacent each end, said chambers differing in sizes, pistons reciprocably mounted in said chambers, a hollow piston stem connecting said pistons and establishing communication between said chambers, one of 25 said pistons having a passage and a port adapted to align with the by-passes to permit pressure from the inlet port to enter the low pressure chamber, by way of the high pressure chamber and hollow piston stem.
- 30 4. A governor valve comprising a casing having high and low pressure chambers provided with inlet and outlet ports respectively, said casing having a by-pass communicating with the high pressure chamber at two points, pistons reciprocally 35
- mounted in said chambers, a hollow piston stem connecting said pistons to cause them to move in unison, one of said pistons having a passage and a port and said passage adapted to align with the by-pass when said piston is in one position to permit pressure from the intake port to enter the low pressure chamber by way of the high pressure chamber, and an adjusting screw carried by the casing and adapted to regulate the 40 stroke of said pistons.
5. A governor valve comprising a casing having high and low pressure chambers provided with inlet and outlet ports, said casing having a by-pass communicating with the 45 high pressure chamber at two points, pistons reciprocably mounted in said chambers, a hollow piston stem connecting said pistons, one of said pistons having a passage and a port communicating with the low 50 pressure chamber at points above and below its respective piston, said casing having a pair of ports, one of which communicating with the high pressure chamber and the other communicating with the inlet port, 55 a by-pass pipe connected to said ports, and valves arranged within said by-pass pipe to regulate the flow of fluid pressure through said by-pass from the inlet port to either side of the piston located in the low pressure chamber and to the high pressure chamber. 60

In testimony whereof I affix my signature.

ALVA K. HINCHMAN.
